UNITED STATES PATENT OFFICE.

JAMES HENDERSON, OF LIMA, OHIO, ASSIGNOR OF ONE-HALF TO JONATHAN K. BRICE, OF SAME PLACE.

ROTARY ENGINE AND PUMP.

SPECIFICATION forming part of Letters Patent No. 330,702, dated November 17, 1885.

Application filed June 11, 1885. Serial No. 168,406. (No model.)

To all whom it may concern:

Be it known that I, JAMES HENDERSON, a citizen of the United States, residing at Lima, in the county of Allen and State of Ohio, have 5 invented a new and useful Rotary Engine and Pump, of which the following is a specification.

My invention relates to rotary engines; and it consists in the improvements hereinafter described and set forth.

10 In the accompanying drawings, forming part of this specification, Figure 1 represents a longitudinal vertical section through the center of the shaft. Fig. 2 represents a transverse vertical section through the center of Fig. 1. Fig. 3 represents a perspective of the inside mechanism removed from the outer casement, and with part of the drum cut away to show working parts. Fig. 4 represents a perspective of the outside of the machine when completed.

In the accompanying drawings like letters refer to like parts.

a a represent the outer casement composed of the base on which it stands, the shell of the 25 machine proper and that of the steam-chest *a'* all in one casting.

P and *P'* represent induction and eduction ports, their function reversing when the motion of the machine is reversed; and *X* and *X'*, 30 auxiliary eduction-ports, whereby steam is exhausted at a favorable point.

S represents a cylindrical cavity which contains the motive mechanism, and *S'* a cylindrical steam-chest which contains the reversing mechanism.

B B represent the head-plates, which are bolted onto the ends of the casement *a a*; *B'* and *B'*, the head-plates bolted onto the ends of the steam-chest *a'*; and *c c*, plates bolted onto 40 plates *B B* to cover openings bored to receive the trunnions *F* and *F'*, as hereinafter described.

D represents a shaft free to rotate in the center of the cylindrical cavity *S* in the casement on bearings bored through bosses in the plates *c c* when actuated by pressure on the vanes or wings *E E'*.

E represents a vane rigidly attached to the shaft *D*, and *E'* a similar vane free to oscillate

between limits on the shaft, both of which extend to a contact with the wall of the cylindrical cavity *S*, their sides being in contact with the inner surfaces of the head-plates *B B*. Contact at the ends and sides is assured and maintained by means of suitable spring packing-strips, (not shown,) for which no novelty is claimed.

F represents a hollow cylindrical drum, which is free to turn on central hollow trunnions, *F'*, at the ends, which fit into openings 6c bored in the head-plates *B B*, and so located as to constantly maintain a contact between an element in the cylindrical surface of the drum *F*, and the packing-strip *J* set into the outer casement midway between the ports *P* 65 and *P'*.

G G represent cylindrical spindles which are free to oscillate in openings in the rim of the drum *F*, so bored that when a spindle is in place an element farthest from the center 7c of the shaft shall be intersected by the surface of the drum. These spindles are composed of two semi-cylinders recessed on the flat sides, so that when placed together they may embrace the vanes *E* and *E'*, making a steam-tight joint 75 between the surfaces brought into contact. Slipping of the semi-cylinders with reference to each other is prevented by suitable dowel-pins at the ends, and contact between the spindles and their seat in the rim of the drum 80 is assured and maintained by suitable packing-strips, (not shown,) for which no novelty is claimed. Sufficient metal is cut away from the rim of the drum *F*, adjacent to the spindles *G G* to permit the vanes *E* and *E'* to oscillate between the limits required in the operation of the machine.

h represents the reversing-valve operated by means of the spindle *D'* and the lever *L*, whereby, in conjunction with the ring *I*, steam 90 may be admitted to either side of the vanes *E* and *E'*, and the other side opened to the exhaust-passage or shut off altogether, at will.

I represents a cylindrical ring turned to fit the inner surface of the steam-chest *a'*, with 95 one side cut out, leaving a space equal to the extreme width of the valve *h* plus the width of the port *P*, and having an elongated slot cut

out of the opposite side to admit steam from the opening Y to the space S' in the steam-chest when the valve is in any position.

When used as a pump, the mechanism remains the same, except that the steam-chest, with its attachments and the passages X and X', are discarded, and the supply and discharge pipes are connected to the passages P and P', respectively.

10 What I claim is—

1. The combination, in a rotary engine, of the casement, providing a cylindrical steam-chamber and a smaller cylindrical valve-chamber, a shaft passing centrally through said steam-chamber and carrying vanes, a cylinder located eccentrically in said chamber, through which said vanes extend, induction and eduction ports communicating with said steam and valve chamber, supplemental ports 15 X X', communicating with steam and valve chamber, a valve located in said valve-chamber for reversing the supply and exhaust of said induction and eduction ports, and alternately throwing either of said supplemental ports into communication with the exhaust, and hand appliances for operating said valve, substantially as set forth.

2. The combination, in a rotary engine, of the casement, providing circular steam-chamber, and a smaller valve-chamber communi-

cating therewith through induction and eduction ports, a shaft passing centrally through said steam-chamber and provided with vanes, a cylinder located eccentrically in said steam-chamber and having said vanes passing through the same, spindles G G, located in cylindrical bearings in said eccentric cylinder, embracing the vanes and flush with the outer surface of said cylinder, the latter being internally enlarged and cut away at the points 40 of location of the vanes, and a valve device located in said valve-chamber for reversing the supply and exhaust, and hand appliances for operating said lever, substantially as set forth.

3. The combination of the larger and smaller circular chambers S S, communicating by ports P P', shaft D, carrying vanes, eccentric cylinder pierced by said vanes, a cylinder or ring, I, located in said smaller chamber and cut away, 50 as described, and an oscillating valve extending into said cut-away portion to shift the cylinder or ring, substantially as set forth.

In testimony whereof I affix my signature in presence of two witnesses.

JAMES HENDERSON.
